UNITED STATES PATENT OFFICE.

RAY F. GILLESPIE, OF HAMILTON, OHIO.

NUT LOCK.

Application filed July 26, 1927. Serial No. 208,486.

My invention relates to nut locks of the base clutch type wherein friction is utilized in connection with rollers and cam grooves in the nut or washer, for coaction with the 5 part to be bolted, for the purpose of securing the nut in locked position. The invention is applicable for use with a lock nut, as well as for use with a washer that is adapted for use with the usual or standard type of nut.

10 My invention consists in certain novel combinations and arrangements of parts whereby the cam rollers are retained in operative position at all times, and whereby the cost of manufacture of a lock nut is reduced to a 15 minimum, and the efficiency of the lock nut is enhanced.

In the accompanying drawings, I have illustrated two examples of the physical embodiment of my invention, wherein the locking device is shown as forming part of a lock nut, and also as forming part of a lock washer adapted for use with a standard nut. These exemplifications show the best modes I have so far devised for the practical application 20 of the principles of my invention, but it will be understood that changes and alterations may be made therein within the scope of my 25 claims, without departing from the principles of my invention.

30 Figure 1 is a face view of a lock nut embodying my invention;

Fig. 2 is an edge view of the lock nut partly broken away to disclose the arrangement of the cam grooves and cam rollers;

35 Fig. 3 is a face view of a lock washer;

Fig. 4 is an edge view of the lock washer;

Fig. 5 is a face view of the base portion of the lock nut, or of the lock washer, with the cam rollers and retaining bridges omitted;

40 Fig. 6 is a view showing one of the rollers; and

Fig. 7 is an end view of this roller.

In carrying out my invention, I have illustrated a standard hexagonal nut 1 having the 45 usual threaded bore 2, and provided with a circular base flange 3. In the face of the base flange or base of the nut, I provide a series of spaced grooves 4 each having a cam wall 5 to form biting faces for the lock nut.

50 In the face of the base, I provide an annular groove 6, and this groove is filled with a ring or band 7 fashioned of music wire, or other suitable material, and this band of wire, where it crosses the grooves, forms retaining bridges as 7'. Preferably the material of

these retaining bridges is somewhat resilient or flexible, to permit action of the lock nut, and the retaining ring or band is fastened in the groove 6 by blows on a center punch to spread the material of the wire or band as 60 indicated at 8 in Fig. 1. The center punch is placed on the wire and the blows are struck by a hammer to spread the material of the wire or band into the face of the base of the washer, and in this manner the retaining 65 bridges are held across the cam grooves.

Before the retaining ring is fastened in the face of the base, the cam rollers 9 are placed in their respective grooves, and each cam roller is provided with an annular groove 70 10 across which the bridge 7' of the retaining ring or band extends. Thus the cam rollers are retained in their grooves and designed to roll up on the cam faces 5 to cause frictional engagement with a support, when the 75 lock nut is screwed home on a bolt.

In Figs. 3 and 4, a washer 11 is shown, and this washer is provided with the grooves 4, cam faces 5, the retaining ring 7 forming the retaining bridges 7', and the same friction rollers 9 are used as in Fig. 1. In addition, the washer is provided with spurs or studs 12 that may engage the face of the standard nut, or of the object being bolted, and the action of the cam rollers 9 in connection with the washer is the same as the cam action of the rollers with the lock nut. 80

In Fig. 5, the numeral 13 indicates a steel ring or band that may be shrunk or otherwise attached on the washer or on the circular base of the nut. The cam grooves 4 and their cam faces may thus be fashioned in the face of the washer or of the base of the nut, before this ring 13 is shrunk or welded on the washer or nut, and in this manner the grooves 4 85 may be fashioned with simplicity and rapidity. The rollers 9 are loosely retained in the mortices or grooves 4 until the cam action

is brought into play, and then the rollers are 90 free to roll up on the cam face 5 and are 100 guided by the retaining bridge 7'. The ring or band 7 is enclosed within the groove 6 as indicated in Fig. 2, and the band does not protrude beyond the face of the nut base or of the washer. The retaining bridge is 105 forced out from the face of the washer or base of the nut, as the cam roller frictionally engages the surface of the object being bolted, but inasmuch as the roller projects beyond the bridge, the bridge does not interfere with 110 the action of the roller.

As before stated, various changes and

alterations may be made in the construction of my lock nut within the scope of my claims without departing from the principles of my invention.

5 Having thus fully described my invention, what I claim as new and desire to secure by Letters Patent is—

1. A lock nut having an annular groove in the face of its base, and spaced cam grooves 10 in said face, a band of resilient material in said annular groove forming bridges across the cam grooves, and friction rollers in said

cam grooves having annular grooves receiving said bridges.

2. A lock nut having an annular groove 15 and intercepting cam grooves in the face of its base, friction rollers in said cam grooves having annular grooves, a resilient wire in said annular groove forming retaining bridges for the grooved friction rollers, and 20 means for securing the wire in the annular groove.
